UNITED STATES PATENT OFFICE.

ROLLO H. VALENTINE, OF CLINTON, ILLINOIS, ASSIGNOR OF ONE-HALF TO RICHARD I. HALL, OF CLINTON, ILLINOIS.

TUFTING DEVICE.

1,374,409.

Specification of Letters Patent. Patented Apr. 12, 1921.

Application filed May 10, 1920. Serial No. 380,251.

To all whom it may concern:

Be it known that I, ROLLO H. VALENTINE, a citizen of the United States, residing at Clinton, in the county of De Witt and State 5 of Illinois, have invented certain new and useful Improvements in Tufting Devices; and I do declare the following to be a full, clear, and exact description of the invention, such as will enable others skilled in the 10 art to which it appertains to make and use the same.

This invention relates to tufting devices and more specifically to an improved hand operated embroidering machine or tufting 15 needle.

One object of this invention is to generally improve upon devices of this character by providing an exceedingly simple and comparatively inexpensive structure which 20 effectually holds the last completed stitch or loop against retraction during both forward and return strokes of the needle when making each subsequent stitch or loop.

A further object of the invention is to 25 provide a device of this character which is exceedingly compact, convenient to thread without use of any threading device or appliance, and may be rotated in the hand of the operator without changing its degree 30 of convenience and comfort with respect to the hand, and without affecting the relative position of the thread being fed thereinto.

Other objects and advantages are pointed 35 out or implied in the following details of description, in connection with the accompanying drawings in which:

Figure 1 is a side elevation of my improved tufting device in position to begin its downward movement for pushing the 40 needle through the cloth or textile base.

Fig. 2 is a view similar to Fig. 1 except that the needle is in its lowermost position with respect to the textile base and to the thread holding sleeve or spring-pressed 45 thread-holder.

Fig. 3 is an enlarged longitudinal sectional view through the center of the handle and spring-pressed sleeve, the needle and compression spring being shown in full elevation.

Fig. 4 is a fragmental detail view of the needle.

Fig. 5 is a rear elevation of the spring-pressed sleeve and of the front end or point 55 of the needle.

Fig. 6 is a sectional view along the line 6—6 of Fig. 3.

Referring to these drawings in detail, in which similar reference characters correspond with similar parts throughout the 60 several views, and in which the cloth or textile base *a* and thread *b* may be of any appropriate kind, the invention consists in the construction and arrangement of parts which will now be described as follows: 65

Referring especially to Fig. 3, it will be seen that the device consists of but four primarily separate members, that is, a tubular handle 1, a needle 2, a pressure member or sleeve 3 and a compression spring 4. 70

The handle 1 is formed with a bore or socket 5 which extends inward from the front end of the handle and terminates in an abutment 6, the rear end portion of the handle being provided with a needle seat, 75 bore or opening 7 which is of relatively small diameter or cross-section in comparison to that of the socket 5. The needle 2 has its rear end tightly fitted in the bore or seat 7, and the front end of the needle 80 extends beyond the front end of the sleeve 3. The sleeve 3 normally extends forward a considerable distance beyond the front end of the handle 1, the rear end of this sleeve being slidably seated in the socket 5, and 85 the socket is sufficiently deep to receive the entire sleeve 3 when the latter is at its rearmost position.

The spring 4 is preferably helical, as shown, and surrounds the intermediate portion of the needle 2, the rear end of this spring being preferably secured to the needle, by solder or other appropriate means, and forms a shoulder on the needle which rests against the abutment 6 and prevents end thrust of the needle rearwardly with respect to the handle. The front end of the spring 4 is soldered or otherwise secured to the sleeve 3, as indicated at 8, and retains the sleeve 3 yieldably in the normal position shown in Figs. 1 and 3. It will be seen, however, that when the handle is pushed down so as to bring the sleeve 3 into contact with the base *a* said sleeve is thereby held against downward movement, and the continued movement of the handle causes a relative movement of the needle 2 and sleeve 3, against the pressure of the spring 4, and this spring-pressure continues during the greater portion of the downward 100 movement of the handle. 105

- and upward movements of the handle and needle. The intermediate portion of the spring 4 is held out of contact with the sleeve 3 by means of the needle, thereby avoiding injury to the spring and interference with the operation of the sleeve 3. The spring also serves to hold the needle and sleeve in proper relation to one another and to the handle 1. Referring to Figs. 4 and 5, it will be seen that the needle is hollow or tubular substantially throughout its length, being provided with a thread-inlet 9 and a thread-outlet 10, the latter being adjacent to the point of the needle and at the front end of the sleeve 3, and therefore, by inserting the end of the thread *b* at 9 and pushing it downward or forward in the needle, its end will pass through or appear in position to be pulled through the outlet 10.
- 20 The sleeve 3 has its front end tapered or reduced, as indicated at 11, to provide a bearing for the needle, and this bearing prevents relative lateral movement of the needle and sleeve 3 so as to keep them concentric.
- 25 Moreover, the sleeve 3 is provided with a series of teeth 12 which extends across the thread-outlet 10, or adjacent to said outlet, so that these teeth engage with the thread at the end of a loop or stitch which has been completed, thereby holding the thread against pulling out of the cloth or base in both downward and upward strokes of the handle and needle, as illustrated in Figs. 2 and 5.
- 30 Referring again to the connection of the spring 4 with the sleeve 3 at 8, it may be well to explain that the spring is here illustrated as being somewhat enlarged to conform to the interior of this sleeve, the latter

being provided with one or more apertures 40 13 through which the solder may be applied to the spring and interior of the sleeve. However, this illustrates only one of many ways in which the spring 4 can be secured to the sleeve 3.

45

Although I have described this embodiment of my invention very specifically, it is not intended to limit the invention to the exact details of construction and arrangement as illustrated, but changes may be 50 made within the scope of the inventive ideas as implied and claimed.

What I claim as my invention is:

A tufting device comprising a one piece rectilinear handle provided with a relatively large central longitudinal bore opening through its front end and occupying substantially half of its length, said handle having a smaller bore leading from its rear end into said larger bore, a one piece needle 55 of uniform cross section and tubular form throughout its length, said needle being rigidly secured in said smaller bore and extending forwardly through said relatively large bore and beyond the front end of the 60 handle, the front end of said needle being sharpened and having an eye, a one piece sleeve slidable in said relatively large bore and extending forwardly therefrom around and spaced from said needle, said sleeve 65 having its front end contracted around said needle, a coil spring in said sleeve and said relatively large bore, means securing the outer end of said spring to said sleeve, and means securing its inner end to said needle. 70

75 In testimony whereof I have hereunto set my hand.

ROLLO H. VALENTINE.
